UNITED STATES PATENT OFFICE.

JOHN STEPHENSON, OF NEW YORK, N. Y.

CAR-TRACK GUARD.

SPECIFICATION forming part of Letters Patent No. 403,302, dated May 14, 1889.

Application filed July 20, 1888. Serial No. 280,514. (No model.)

To all whom it may concern:

Be it known that I, JOHN STEPHENSON, a citizen of the United States, residing at New York, in the county and State of New York, 5 have invented certain new and useful Improvements in Car-Track Guards, of which the following is a full, clear, and exact specification.

The velocity with which cable cars move is apt to deceive persons on the street, causing accidents sometimes fatal. It is therefore important to have a guard spread over the track beyond the wheels. Guards have been used suspended from the car-body; but such are 15 inefficient because of the large space above the street-surface at which the lower margins of such guards are placed to provide for the crush of the car-springs and tossing motion of the car-body. Experience has shown that 20 such guards have caused accidents to terminate fatally which would otherwise have been less serious.

My invention consists in means for obviating these difficulties, and said means are fully 25 set forth hereinafter, and illustrated in the accompanying drawings, in which—

Figure 1 is a plan of sufficient of a tram-car to illustrate my invention. Fig. 2 is a side elevation.

30 A cable car has been devised well adapted to carry a track-guard adjusted as near the road-bed surface as desired, and I make use of such a car to so support the guard that it may be held in unvarying elevation, unless 35 necessary to surmount some overcomable obstacle, and in such case accomplish the result by automatic action.

My invention assumes that there is a truck having its sills suspended beneath the axle-boxes 40 by pendants 4, integral with the box-shells, and the ends of the truck-sills extending endward beyond the axle-boxes. To such extended sills is appended a fence or guard, 130, reaching from side to side of the track, 45 and from the sill ends extending in advance of the truck. The fence part of the guard may be a straight line or any deviation therefrom, but preferably the two sides of an angle, with the point central with the central 50 line of the car, or over the slot-rail, each leg

of the angle connected with an end of a truck-sill. There is a connection, preferably articulated, permitting the nose of the guard to be elevated by any overcomable obstruction, and the guard when in normal 55 position sustains itself with its nose above contact with the road-bed. One jointed connection is shown, the joints being formed by pivots.

Joint-irons 132 are connected with the 60 truck-sills by the bolts 131 near the end of each sill 5, or preferably there is one long bolt, each end constituting a pivot, uniting the ends of the adjacent joint and sill. Each joint-iron is secured to one end of the guard, 65 and the other end of each joint-iron, after passing the joint-bolt, continues along the vertical face of the sill end for a desired distance and turns under the sill to form a finger, 132, so as to contact with the sill and 70 prevent the outer end of the joint-iron with its fence-section from falling nearer the track than desirable. The central part of the long bolt may be utilized, by surrounding it with a pipe or tube, 133, of determined length, to 75 fit between the truck-sill ends, adapted to prevent them from being forced nearer to each other, while the long bolt secures the sill ends from spreading.

The construction is strengthened by having the sill ends banded with iron, through which the joint-bolts pass.

I do not here claim the arrangement of the sills and boxes and the construction of the truck-frame shown, as the same constitute 85 the subject of a separate application for Letters Patent, Serial No. 250,508.

I claim—

1. A car having a truck-frame supported at the ends of the axles by pendants integral 90 with the axle-box shells, and having the truck-sills extending endward before the car-wheels, with a car-track guard pivoted to the ends of the truck-sills and adapted to automatically push from the track accidental obstructions 95 and overcome surmountable obstacles, substantially as described.

2. A car-track guard extending across the track in advance of the car-wheels and jointed to the sills, the wings of the guard provided 100

with metal joint-plates extending beyond the wings and joint-bolts and continuing along the truck-sills, with the ends of the joint-plates bent under the sills and adapted to 5 contact with the sills to counterpoise the track-guard and hold its guard at its desired elevation above the road-surface, substantially as shown and described.

In testimony whereof I have signed my name to this specification in the presence of 10 two subscribing witnesses.

JOHN STEPHENSON.
